Application October 26, 1953, Serial No. 388,403

3 Claims. (Cl. 257—2)

This invention relates to a cooling water arrangement for degreasers.

It is common practice for degreaser manufacturers to employ both a water condensing coil on the interior of a degreaser tank as well as a water jacket on the exterior of the tank. These two systems are generally tied in series and water is introduced first into the jacket where it circulates therethrough into the cooling coil, then through the cooling coil and into a drain. It is also common practice to insert the cooling water temperature regulator so that the flow of water coming out of the cooling coil circulates around the thermal-bulb of this control. Thus as the temperature of the cooling water increases, the main valve of the control opens, permitting an increased amount of cool water to circulate through the system. As the temperature of the water coming out of the condensing coil cools to the desired temperature, the main valve closes, a slight flow of water circulating through the by-pass on this control to enable the change in water temperature to occur at the thermal-bulb almost as quickly as it occurs in the coil.

One of the disadvantages of this arrangement is that by the time the control receives water of a temperature sufficiently high to cause it to open, the temperature of the water in the coil is constantly increasing and in order for the fresh cold water to reach the coil it has to travel first through the water jacket and then into the coil, which causes a slight increase in the vapor level as well as a slow, sluggish action of the control. Also, cold water entering the water jacket would tend to condense moisture on the opposite side of the jacket, within the degreasing tank, and this moisture in turn tends to hydrolyze with the degreasing solvent with a resultant break-down into an objectionable acid condition.

It is accordingly a principal object of the present invention to provide an improved cooling water arrangement wherein the cooling water flows first through the condensing coil and then into the external water jacket, and wherein the temperature bulb of the water regulator is located intermediate the outlet of the condensing coil and the inlet of the water jacket, thus enabling fresh cold water to first enter the bottom section of the condensing coil, circulate upward through this coil and out and around the temperature bulb of this control, from which point it then enters the water jacket, circulates through this jacket and is then discharged into an open drain. This improved arrangement has the following advantages: Colder water entering the coil effects more efficient vapor level control. The sudden chill is also removed from the water so that by the time the water reaches the upper sections of the coil it is generally above the dew point and minimizes thereby the possibility of moisture condensing on the upper section of the coil. Also, as the temperature of the water in the coil increases it immediately causes the regulator to operate, cold water immediately entering the coil to cause a reduction in coil water temperature. Thus, the warm water leaving the regulator enters the water jacket at a temperature above the dew

point, which minimizes the possibility of moisture formation around the interior of the water jacket, yet this water is still at a temperature low enough to affect good control of the free board zone.

5 Other objects of the present invention are to provide an improved cooling water arrangement which provides for more efficient control of the vapor level, reduces water requirements for heat balance and which reduces the possibility of moisture condensing inside the tank and thereby reduces the resulting decomposition of degreasing solvent which increases the life of the degreaser by preventing the formation of corrosive solutions.

Other objects of the present invention are to provide a cooling water arrangement for degreasers bearing the above objects in mind which is of simple construction, inexpensive to manufacture, has a minimum number of parts, is easy to use and efficient in operation.

For other objects and a better understanding of the invention, reference may be had to the following detailed description taken in connection with the accompanying drawing, in which:

Figure 1 is a fragmentary perspective view of a degreaser, shown partly broken away, and showing the cooling water arrangement embodying the features of the present invention incorporated thereon, and

Figure 2 is an enlarged side elevational view of a water regulator, shown partly broken away to show the interior construction thereof.

Referring now more in detail to the drawing, in which similar reference numerals identify corresponding parts throughout the several views, 10 represents a degreaser including a main tank 11 and a side tank 12, substantially as illustrated.

35 An external water jacket 13 extends around the main tank 11 and side tank 12, a baffle or dam 14 being provided at one corner thereof. An outlet 16 is provided for the jacket, the outlet 16 being provided on one side of dam 14 and being connected to a drain by means of suitable piping, not shown. An inlet 15 for the jacket is also provided on the other side of dam 14.

40 A condensing coil 17 is mounted in the top of the side tank 12, the inlet of the coil 17 being releasably connected to an inlet 18 by means of a pipe union 19, the inlet 18 being suitably mounted in the end wall of the side tank 12 below jacket 13. The outlet end of the coil 17 is releasably connected to an outlet 20 by means of a pipe union 21, the outlet 20 being suitably mounted in the end wall of side tank 12 above the jacket 13.

45 In the practice of the present invention, a pipe elbow 22 is provided on the outer end of condenser coil inlet

50 18 and serves to mount a vertical pipe 23 connected to a second vertical pipe 24 directly above by means of a pipe union 25. A second elbow 26 is provided on the upper end of vertical pipe 24 and serves to mount a horizontal pipe 27 which is connected to the outlet of a water regulator or thermostatic valve 28 of any suitable type which bases its operation and action on the temperature of the cooling liquid.

55 A second horizontal pipe 29 is connected to the inlet of the water regulator 28, a liquid strainer 30 being connected to the outer end of pipe 29 and connecting with a suitable source of cooling water, not shown. Thus, cooling water will flow in the direction of the arrows of Figure 1 through strainer 30

60 into pipe 29, through the water regulator 28 into pipe 27, and downwardly through vertical pipes 24 and 23 into the inlet 18 of the condenser coil 17.

65 The valve 28 is of well known construction and includes a hollow depending portion 31 within which is housed the usual temperature bulb or thermostatic control 32 (Fig. 2).

70 A pipe 33 is screwed onto the externally threaded bottom of the depending portion 31 and houses there-

within the temperature bulb 32. A horizontal pipe 34 is screwed into the horizontal outlet of T 33 and is connected to a vertical pipe 35 by means of elbow 36. The lower end of vertical pipe 35 is connected to a second vertical pipe 37 directly below by means of a pipe union 38, the lower end of pipe 37 being connected to the inlet 15 of water jacket 13 by means of an elbow 39.

A vertical pipe 40 is screwed into the bottom outlet of T 33, the lower end of pipe 40 being connected to the outlet 20 of coil 17 by means of T 41.

Thus, cooling water leaving from the outlet 20 of condenser coil 17 is conducted upwardly through vertical pipe 40 into the T 33 where it contacts the temperature bulb 32 as it passes into the horizontal pipe 34 and downwardly into the water jacket inlet 15 through the pipes 35 and 37. Thus, the water regulator or thermostatic valve 28 is controlled by the temperature of the water intermediate the outlet of the condenser coil 17 and the inlet of the water jacket 13, providing better and more accurate control of the height of the vapor level than heretofore achieved.

This improved method of installing the water temperature regulator in between the water jacket and coil now enables the fresh cold water to first enter the bottom section of the condensing coil, circulate upward through this coil and out and around the temperature bulb of this control, from which point it then enters the water jacket, circulates through this jacket and is then discharged into an open drain. The following has been accomplished: Colder water entering the coil effects more efficient vapor level control. The sudden chill is also removed from the water so that by the time the water reaches the upper sections of the coil it is generally above the dew point and minimizes thereby the possibility of moisture condensing on the upper section of the coil. Also, as the temperature of the water in the coil increases it immediately causes the regulator to operate, cold water immediately entering the coil to cause a reduction in coil water temperature. Thus, the warm water leaving the regulator enters the water jacket at a temperature above the dew point, which minimizes the possibility of moisture formation around the interior of the water jacket, yet this water is still at a temperature low enough to affect good control of the free board zone. With this arrangement the following is also accomplished: More efficient control of the vapor level, minimum water requirements for heat balance, and minimum possibility of moisture forming and causing a resultant decomposition of the degreasing solvent, which in turn tends to increase the life of the degreaser by reducing the possibility of corrosive substances.

While various changes may be made in the detail construction, it shall be understood that such changes shall be within the spirit and scope of the present invention, as defined by the appended claims.

5. What is claimed as new is:

1. A cooling water arrangement for a degreaser comprising a main tank and a side tank in communication with each other, an external water jacket surrounding said main and side tanks, a baffle within said water jacket, 10 an inlet in said jacket on one side of said baffle, an outlet in said jacket on the other side of said baffle, an elongated vertically disposed helical condensing coil mounted within the top of said side tank and exposed to the vapors of degreasing solvent to be condensed, an inlet for said coil, an outlet for said coil, first pipe means for supplying cooling liquid to said inlet of said condensing coil, valve means mounted in said first pipe means, a pipe T having one end substantially closed to the flow of cooling liquid, said end being connected to 20 said valve means, a thermally responsive element disposed within said pipe T, control means cooperatively associated with said thermal element and said valve means to regulate said valve means, second pipe means connecting a first outlet of said pipe T with said outlet of 25 said condensing coil, a third pipe means connecting a second outlet of said pipe T with said inlet of said water jacket, whereby the vapor level of said degreasing solvent is controlled and whereby moisture is substantially precluded from condensing on the surface of said coil and outer jacket.

2. A cooling arrangement according to claim 1, wherein 30 in said vertically disposed helical coil extends substantially the full horizontal dimension of said side tank.

3. A cooling water arrangement according to claim 2, 35 wherein a portion of said vertically disposed helical coil is in the vapor zone of said degreaser and a portion of said helical coil is disposed in the free board zone of said degreaser.
